UNITED STATES PATENT OFFICE.

ROBERT HAUSDORF, OF BOCHUM, GERMANY.

APPARATUS FOR DISCHARGING LIQUIDS FROM BARRELS INTO STORAGE-RECEPTACLES.

946,039.

Specification of Letters Patent. Patented Jan. 11, 1910.

Application filed May 28, 1909. Serial No. 498,929.

To all whom it may concern:

Be it known that I, ROBERT HAUSDORF, a citizen of the German Empire, and resident of 49^a Kanalstrasse, Bochum, Germany, have invented certain new and useful Improvements in Apparatus for Discharging Liquids from Barrels into Storage-Receptacles, of which the following is a specification.

10 This invention relates to apparatus for discharging liquids, more particularly inflammable liquids, from barrels into storage receptacles, and the characteristic feature of this apparatus is that the bung-hole, at the 15 upper part of the barrel, is connected by means of a flexible pipe to a rigid discharge-pipe at a lower level, while the air or gas space of the storage receptacle is connected by means of a second flexible pipe to a pipe 20 extending nearly to the bottom of the barrel. If the barrel is turned so that the bung-hole faces downward, there is always in respect of the rigid discharge pipe, or bend of the siphon, a hydrostatic head which 25 automatically operates the discharge. It is immaterial if this "head" is lost in the course of the discharge, inasmuch as the initiated siphon action in any case continues the discharge.

30 The drawing shows one form of the new apparatus, Figure 1 being an elevation and Fig. 2 a plan view.

In a substantially T-shaped pit *a*, are mounted two pairs of parallel beams *b*, carrying rollers *c*, which are adapted to support the barrel *d*, to be emptied. The upper surface of rollers *c*, is on a substantial level with the top of said pit, so that the heavy full barrel may be readily transferred from 40 floor *e* to rollers *c*, while the pit *a*, prevents the spreading of the inflammable liquid in case of breakage. The barrel is first placed upon rollers *c*, with the bung-hole *e* facing upward; then the union or coupling *g*, 45 threaded at *f*, is screwed into the bung-hole. From the union a pipe *h* extends into the barrel nearly to the bottom of the latter. There is an annular passage *i* in the union, around the pipe *h*. The pipe *h* is connected 50 by means of a flexible hose or pipe *k* and union *l* to a pipe *m* leading to the air-space of the storage receptacle *w*. The annular passage *i* is connected by a flexible hose or pipe *n* to a union *o* and pipe *p* leading to 55 the receptacle *w*. The barrel *d* is then ro-

tated through an angle of 180° into the position indicated by dotted lines, whereupon the flow of liquid from the barrel to the receptacle *w* automatically takes place, the air from the receptacle *w* flowing through 60 pipes *m*, *k*, and *h* to the barrel. The annular passage *i* forms a small well at the bottom of the barrel so that the latter is completely emptied. At the termination 65 of the discharge from the barrel the last portion of liquid in the pipe *n* also flows to the receptacle *w*, when the barrel *d* is returned to its original position. This is an important advantage of the apparatus; with the ordinary apparatus heretofore used a 70 certain quantity of residual liquid is always left in the barrel and must be separately discharged into some kind of receptacle, without means of guarding against explosion. 75

The roller-support *c* affords a steady seat for the barrel *d* and greatly facilitates the turning of the latter, which is an important advantage in view of the weight of the barrel. It also obviates strain on the flexible 80 pipes.

Means are provided for closing pipes *m* and *p*, in order to prevent entrance of air to the storage receptacle when liquid is subsequently drawn from the latter. For this 85 purpose the said pipes are provided with a double cock *q* connected by lever *r* and rod *s* to a rod *t*. Springs *u* normally thrust the lever *r* to the left, so that the cock closes the pipes. The union *g* has a projection *v*, which 90 during rotation of the barrel abuts against rod *t* and moves the same to the right, compressing springs *u*. The cock *q* is thus operated to open the pipes *m* and *p* for the discharge. When the barrel is rotated to its 95 original position again the pipes are automatically closed.

What I claim is:—

1. Apparatus of the character described, comprising a pit, barrel-supporting rollers 100 mounted therein, a pair of pipes adapted to enter a storage tank, a barrel-coupling, and a pair of hose connecting the coupling with said pipes, the length of said hose being sufficient to permit a semi-rotation of the barrel. 105

2. Apparatus of the character described, comprising a pit, barrel-supporting rollers mounted therein and projecting into substantial alinement with the top of the pit, a pair of pipes adapted to communicate with 110

the top and bottom of a storage tank, a barrel-coupling, and a pair of hose connecting the coupling with said pipes, the length of said hose being sufficient to permit a semi-
5 rotation of the barrel.

3. Apparatus of the character described, comprising a series of rollers adapted to support a barrel, a barrel-coupling having an abutment, a pair of pipes adapted to
10 enter a storage tank, a pair of flexible hose

connecting the coupling with said pipes, and means actuated by the abutment for controlling said pipes.

Signed by me at Barmen, Germany, this 17th day of May, 1909.

ROBERT HAUSDORF. [L. s.]
